CIGARETTE CASE AND DISPENSER

George H. Hutaff, Jr., Wilmington, N. C.

Application November 4, 1937, Serial No. 172,795

3 Claims. (Cl. 312—78)

My invention relates to new and useful improvements in a cigarette case and dispenser and has for its principal object the provision of a case adapted for holding a plurality of cigarettes and the provision of means for delivering a single cigarette at a time in position to be grasped and removed by the user.

Another object of the invention consists in the provision of a device of the character described in which a single cigarette at a time is adapted to be delivered through an opening in the case, the position of the cigarette being changed as it is projected through the opening so that an end thereof projects forwardly towards the user and adapted to be grasped to be totally removed from the case.

A still further object of the invention consists in the provision of a case and dispenser of the character described in which a slideable plunger is provided, said slideable plunger being normally positioned to support a plurality of cigarettes in the case but adapted to be moved to allow a single cigarette to drop in front of the forward edge thereof and to be discharged through an opening in the case as the plunger is returned to its normal position.

A further object of the invention resides in the provision of novel means for operating the slideable plunger, said means including a key having a horizontally extending pin engageable with an inclined member or portion carried by or formed as a part of the slideable plunger.

With the above and other objects in view, which will appear as the description proceeds, my invention consists in the novel details of construction, and arrangement of parts, described in the following specification and illustrated in the accompanying drawing, and while I have illustrated and described the preferred embodiments of the invention, as they now appear to me, it will be understood that such changes may be made as will fall within the scope of the appended claims.

In the drawing:

Fig. 1 is a front elevation of the case and dispenser.

Fig. 2 is an end elevation.

Fig. 3 is a top plan with the cover removed.

Fig. 4 is a horizontal section on the line 4—4 of Fig. 1 looking in the direction of the arrows.

Fig. 5 is a transverse vertical section on the line 5—5 of Fig. 3 looking in the direction of the arrows.

Fig. 6 is a longitudinal vertical section on the

line 6—6 of Fig. 5 looking in the direction of the arrows; and

Fig. 7 is a transverse vertical section on the line 7—7 of Fig. 3 looking in the direction of the arrows.

In carrying forth my invention I provide a box-like structure or case including a front face 1 having an elongated opening 2 therein, a rear face 3, end faces 4 and 5, and bottom 6. A foot or supporting structure 7 is formed at each corner 10 and at 8 I have provided a readily removable cover having depending flanges adapted to telescope the front, back and end faces.

Supported on the bottom 6, by means of a rear flange 9 and side flanges 10 is a frame-like 15 structure indicated generally at 11 and provided with an opening shown at 12. Bent inwardly from one of the side flanges 10 is an extension indicated at 13 which extends under the forward edge of the frame 11 as shown more particularly 20 in Fig. 4 of the drawing and extending upwardly from the forward edge of the frame 11, adjacent the opposite end flange of the frame is the projection 14 having a threaded opening therein to receive the screw 15 which secures a plate 16 to 25 the extension, this plate 16 being received in the opening 2 of the box-like structure or case adjacent one end thereof, as shown more particularly in Figs. 1 and 4 of the drawing, to properly position the frame within the box-like structure 30 or case and to normally prevent removal thereof although permitting removal when the plate is detached from the extension.

Positioned on the frame-like structure 11 and adapted for slideable movement is a plunger 17 35 having at its forward edge, adjacent one side edge, a cut-out portion providing the surfaces 18 and 19, one at right angles with respect to the other. This cut-out portion is at that side of the frame structure 11 having the upwardly directed extension 14. At its rear edge the plunger is provided with the downwardly extending flange 20 which is adapted to engage the rear edge of the cut-out portion or opening of the frame 11 to limit the rearward movement of the plunger. 40 The plunger is provided rearwardly of its forward edge with the downwardly directed flanges 21 and 22 which are adapted to engage the forward edge of the opening in the frame-like structure to limit the forward movement of the plunger, 45 the plunger being normally held in its forward position by the coiled spring 23, one end of which is secured to the downwardly directed flange 20 of the plunger while the opposite end is connected to the inwardly directed extension 50 55

13 formed on the frame 11. Extending upwardly from the top face of the plunger, adjacent that end or edge removed from the cut-out portion of the plunger is a plate 24 having the inclined or beveled edge 25.

Secured to the rear edge of the frame structure 11, by means of the screws 26 or other suitable fastenings, is a vertically extending plate 27 which will normally rest against the rear face 3 of the case or box-like structure. Formed as an integral part of the plate 27 and extending downward is a plate 28 having the downwardly directed front flange 29 and end flanges 30 and 31, the flange 31 being positioned between the end 5 of the case and the upwardly directed plate 24 carried by the slideable plunger. The flange 31 is also provided with the vertically extending opening 32 for a purpose which will be presently described. It will be noted that the plate 28 overlies a portion of the slideable plunger 17 as quite clearly shown in Figs. 3, 5 and 7 of the drawing.

For operating the slideable plunger 17 I provide the key including the vertically extending portion 33 and horizontal portion 34, this key being slidably mounted on the end of the box-like structure or case by the plate 35 secured to the end of the case by means of the screws 36 and 37. The screw 37, as shown more particularly in Fig. 4 of the drawing, also extending into a threaded opening in the side flange 10 of the frame-like structure 11 to cooperate with the plate 16 to connect the frame within the case or box. The vertically extending portion of the key is provided on its inner face with the pin or projection 38 which carries the roller 39 which normally engages and operates over the inclined or beveled edge 25 of the plate 24. It will be noted that the pin or projection 38 extends through and operates in the vertically extending opening 32 formed in the depending flange at the end of the plate 28.

Having fully described the detailed construction of my device it is thought that the construction and operation will be clearly understood. I have provided a case or box-like structure in which may be readily placed or removed a frame-like structure carrying a slideable plunger and an over-hanging plate which acts as a support and feed for the cigarettes to be held in the case and dispensed. Normally the parts will be in the position shown quite clearly in Figs. 3, 5 and 7, of the drawing, and cigarettes will be supported on the inclined plate 28 as well as on the forward portion of the slideable plunger. I have only illustrated a single cigarette *a* mounted on the slideable plunger 17. When it is desired to remove a cigarette the operator engages the horizontal portion 34, of the key, and presses downwardly thereon. This lowers the pin or projection 38 with its associated roller 39 and the roller operated against the inclined or beveled surface of the plate 24 forces the plunger 17 rearwardly against the action of the coiled spring 23. This permits the cigarette *a* to drop down onto the forward edge of the frame 11 in front of the forward edge of the plunger 17. An end of the cigarette, extends behind the upwardly directed portion or extension 14, while the remaining portion thereof extends parallel with the opening 2.

When the key is released the spring 23 will draw the plunger forwardly and the end of the cigarette into engagement with the projection 14. A continued forward movement of the plunger carries that portion of the cigarette which extends parallel with the opening 2 through the opening and turns the same into the position shown in Fig. 4 of the drawing so that the cigarette extends forwardly of the case or box-like structure in position to be withdrawn by the operator. The cut-out portion in the plunger, which forms the walls or surfaces 18 and 19 permits the cigarette to turn as described and when turning the end of the cigarette engages the wall or surface 18 while the side thereof engages the surface or wall 19. The operation of the plunger may be repeated to dispense the desired number of cigarettes and it will be particularly noted that the extension 14 cooperates with the plunger in turning the cigarette to project forwardly. When it is desired to remove the operating structure and cigarette supports this may be done by removing the screws 15 and 37. With the screw 15 removed the plate 16 may be removed from the opening 2 and the structure referred to raised and removed as a unit.

Having fully described my invention what I claim as new and desire to secure by Letters Patent is:

1. A device of the character described including a case for receiving a plurality of cigarettes, said case including a front portion having a longitudinally extending discharge opening therein, means for delivering a single cigarette to a position extending parallel with the discharge opening, and means operable for discharging the cigarette through the discharge opening and during such discharge turning the same to project forwardly of the case towards the operator and to be held until finally withdrawn for use.

2. A device of the character described including a case to receive a plurality of cigarettes and provided with a discharge opening, a plunger slidably mounted in the case for discharging the cigarettes, one at a time, through the discharge opening, an upwardly extending beveled projection carried by the plunger, means overlying the projection for directing the cigarettes onto the plunger and towards the discharge opening, and a key slidably mounted on the case, said key having a lateral extension engageable with the beveled surface of the plunger projection for operating the plunger.

3. A device of the character described including a case to receive a plurality of cigarettes and provided with a discharge opening, a readily insertable and removable unitary structure secured in the case, said unitary structure including a frame, a plunger carried by and slideable relative to the frame and a member connected to the frame and overlying the upper surface of the plunger, a member detachably connected to the frame and received in the discharge opening of the case to hold the unitary structure therein against accidental displacement, and means for operating the plunger to discharge a single cigarette at a time through the discharge opening of the case.

GEORGE H. HUTAFF, JR.
